DESIGN FOR GOGGLES

Nicholas T. Baldanza, Passaic, N. J.

Application February 21, 1940, Serial No. 90,406

Term of patent 3½ years

To all whom it may concern:

Be it known that I, Nicholas T. Baldanza, a citizen of the United States, residing in Passaic, county of Passaic, State of New Jersey, have invented a new, original, and ornamental Design for Goggles, of which the following is a specification, reference being had to the accompanying drawing, forming part thereof:

Figure 1 is a front elevation of a goggle showing my new design;

Figure 2 is a perspective view thereof.

I claim:

The ornamental design for goggles, as shown.

NICHOLAS T. BALDANZA.
